[57] CLAIM

The ornamental design for a set of rear fins for a vehicle, as shown and described.

DESCRIPTION

FIG. 1 is a front perspective view of a set of rear fins for a vehicle of the invention, as viewed from the top, left-hand side with the rear fins closed, the vehicle being shown in phantom and forming no part of the design;

FIG. 2 is a front view of a set of rear fins for a vehicle of the invention, with the rear fins closed, the vehicle being shown in phantom and forming no part of the design;

FIG. 3 is a side view of a set of rear fins for a vehicle of the invention with the rear fins closed, the vehicle being shown in phantom and forming no part of the design;

FIG. 4 is a top plan view of a set of rear fins for a vehicle of the invention with the rear fins closed, the vehicle being shown in phantom and forming no part of the design;

FIG. 5 is a rear view of a set of rear fins for a vehicle of the invention with the rear fins closed, the vehicle being shown in phantom and forming no part of the design;

FIG. 6 is a front perspective view of a set of rear fins for a vehicle of the invention, as viewed from the top, left-hand side, with the rear fins open, the vehicle being shown in phantom and forming no part of the design;

FIG. 7 is a front view of a set of rear fins for a vehicle of the invention, with the rear fins open, the vehicle being shown in phantom and forming no part of the design;

FIG. 8 is a side view of a set of rear fins for a vehicle of the invention, with the rear fins open, the vehicle being shown in phantom and forming no part of the design;

FIG. 9 is a top plan view of a set of rear fins for a vehicle of the invention, with the rear fins open, the vehicle being shown in phantom and forming no part of the design; and,

FIG. 10 is a rear view of a set of rear fins for a vehicle of the invention, with the rear fins open, the vehicle being shown in phantom and forming no part of the design.
